UNITED STATES PATENT OFFICE.

OSCAR M. LEICH, OF GENOA, ILLINOIS, ASSIGNOR TO CRACRAFT-LEICH ELECTRIC COMPANY, OF GENOA, ILLINOIS, A CORPORATION OF ILLINOIS.

SIGNALING SYSTEM.

938,155.

Specification of Letters Patent. Patented Oct. 26, 1909.

Original application filed December 10, 1908, Serial No. 466,777. Divided and this application filed February 15, 1909. Serial No. 478,082.

To all whom it may concern:

Be it known that I, OSCAR M. LEICH, citizen of the United States, residing at Genoa, in the county of Dekalb and State of Illinois, have invented a certain new and useful Improvement in Signaling Systems, of which the following is a full, clear, concise, and exact description, reference being had to the accompanying drawings, forming a part of this specification.

My invention relates to signaling systems, and is more particularly allied to railway signaling systems. This invention is a divisional application of my former application, Serial No. 466,777, filed Dec. 10, 1908.

Generally speaking, my invention comprises a metallic telephone circuit, over which telephone conversations can be carried on metallically, and in addition, the arrangement on said metallic circuit of a plurality of non-interfering telephone circuits, all in combination with selective signaling means for calling the telephone instruments associated with the aforesaid metallic telephone circuit, and selective signaling means for sub-station tandem telephones arranged on the local tandem circuits. In other words, it is a complete system of through telephone service, and local or block telephone service in combination with selective signaling means to effect selective calls between the various stations and circuits.

I will describe my invention more in detail by reference to the accompanying drawings illustrating the preferred embodiment, in which:

Figure 1 sets forth diagrammatically the general circuit arrangements, and Fig. 2 sets forth more in detail the selector equipment for calling the metallic stations.

My general system, as shown in Fig. 1, comprises a central station A, and sub-stations B, C, D, E, F, G and H. Line wires 1 and 2 unite the various stations, although in the preferred form, which I herein indicate, repeating coils 3, 3 are interposed at inter-

vals to establish the telephonic continuity of the circuit metallically, and I have called the line wires 1 and 2 the same throughout the various stations.

I connect telephone circuits metallically from the terminals 4 and 5, which telephones are shown more in detail in Fig. 2, and which telephones consist of the receiver 6, transmitter 7, switch-hook 8, and induction coil 9. These telephone circuits are adapted for communication with the dispatcher's telephone set consisting of the head receiver 6, induction coil 9, and transmitter 7, all metallically over the circuit, as shown, there being shown in Fig. 1, besides the train dispatcher's telephone set, eight metallic telephone stations.

It is necessary to call the various stations selectively, and for this purpose, the train despatcher is provided with a key 10 and battery 11, so that he can transmit metallic impulses over the line. These metallic impulses actuate a relay 12, which relay, when receiving impulses, operates the relay 13, thereby to actuate the pivoted pawl 14, which rotates the wheel 15. The wheel 15 is provided with a contact arm 16, and with openings which permit the contact arm 16 to be in contact with a different opening for each station on the line. The first impulse of the relay 12 also operates the relay 17, which thereby releases the clock mechanism 18, and permits it to travel in contra-clockwise direction. The clock mechanism 18 is provided with a contact member 19. It is designed that the clock mechanism 18 shall move more slowly than the wheel 15 is moved forwardly by the impulses. When the wheel 15 is stepped up to its proper contact-making position, as shown in Fig. 2, the wheel 15 is finally overtaken by the clock mechanism 18, and circuit is closed through the relay 20, which thereby operates the local signal 21, and at the same time, the relay 20, through the auxiliary winding 22, locks itself in position until released by the oper-

ator through the action of the key 23. After making contact, the clock mechanism 18 continues to revolve until its contact member engages the segment 24, whereupon circuit is closed through the relay 25, which releases the wheel 15, and allows it, by virtue of the weight 26, to reach its normal position, whereupon circuit is opened through the springs 27 and 28 by the insulating strip 29, which again opens the circuit through the relay 25, and allows all parts to be restored to normal ready for another call. It will thus be seen that the central station operator can call selectively either one of the stations from A to H, and can converse with them metallically.

In order to provide further necessary communicational advantages over the circuit, I insert repeating coils 3, as before stated, which subdivide the circuit 1-2 into a plurality of tandem telephone circuits, which are connected at the contacts 30 and 31,—that is, they are taken off from the central portions of the repeating coils 3, and also from the central portion of the windings of impedance coils 32. Thus, a plurality of ground telephone circuits are established. For instance, the ground circuits between stations A, B, and the left-hand side of station C, can communicate with each other; likewise, stations E, F and G; but the repeating coils prevent intercommunication over these ground circuits from one tandem circuit to the other. These grounded telephone circuits at the stations C, E, and G, for instance, are provided with keys 33, which permit a station telephone set at said stations to be connected to either the right-hand or left hand tandem, thus obviating the necessity of two telephone sets at these stations. The telephone sets at said stations comprise the transmitter 34, receiver 35, induction coil 36, and switch-hook 37; the instrumentalities above mentioned being shown only in connection with the station A, but their connections at the other stations at the terminals 30 and 31 will be obvious. These sub-station block telephones are also provided with a reverse key 38, which permits the reversal of the pulsating current generator upon their circuits, thus making it possible to send either positive or negative pulsating current over the tandem circuit. For instance, station C, with positive battery current, can call station D, and with negative battery current can call station E, or the reverse, so that the three stations C, D and E can signal between themselves selectively. I find it of great advantage not to provide a great number of repeating coils in the circuit, and for this reason I provide the impedance coils 32, which impedance coils permit of telephones being associated on the tandem circuit or block circuit.

From the foregoing, it will be seen that I

can signal selectively over the metallic circuit, and also selectively over the block circuit.

While I have herein shown and particularly described the preferred embodiment of my invention, I do not limit myself to the precise construction and arrangement herein set forth, but

Having thus described my invention, what I claim as new and desire to secure by Letters Patent is:

1. A telephone system comprising a metallic circuit, repeating coils for maintaining the telephonic continuity of said metallic circuit, telephonic appliances at a central station and a plurality of sub-stations arranged for the transmission of voice currents metallically over said circuit, means at the central station for selectively calling either sub-station, a plurality of additional non-interfering telephone circuits, arranged end to end and superposed on said metallic circuit and a return circuit, telephonic appliances for each of said additional circuits, and reactive means for preventing telephonic interference between conversations simultaneously carried on over all of the telephonic circuits aforesaid.

2. A telephone system comprising a metallic circuit, repeating coils for maintaining the telephonic continuity of said metallic circuit, telephonic appliances at a central station and a plurality of sub-stations arranged for the transmission of voice currents metallically over said circuit, means at the central station for selectively calling either sub-station, a plurality of additional non-interfering telephone circuits arranged end to end and superposed on said metallic circuit and a return circuit, a plurality of telephonic appliances for each of said additional circuits, signaling devices whereby the plurality of telephonic appliances of each additional circuit can call themselves selectively, and reactive means for preventing telephonic interference between conversations simultaneously carried on over all of the telephonic circuits aforesaid.

3. A telephone system comprising a metallic circuit, repeating coils for maintaining the telephonic continuity of said metallic circuit, telephonic appliances at a central station and a plurality of sub-stations arranged for the transmission of voice currents metallically over said circuit, means at the central station for selectively calling either sub-station, a plurality of additional non-interfering telephone circuits, arranged end to end and superposed on said metallic circuit and a return circuit, and reactive means for preventing telephonic interference between conversations simultaneously carried on over all of the telephonic circuits aforesaid.

4. A telephone system comprising a metal-

lic circuit, telephonic appliances at a central station and a plurality of sub-stations arranged for the transmission of voice currents metallically over said circuit, means at the central station for selectively calling either sub-station, a plurality of additional non-interfering telephone circuits, arranged end to end and superposed on said metallic circuit and a return circuit, and reactive means for preventing interference between

conversations simultaneously carried on over all of the telephonic circuits aforesaid.

In witness whereof, I hereunto subscribe my name this 6th day of February, A. D. 1909.

OSCAR M. LEICH.
